UNITED STATES PATENT OFFICE.

STEPHEN O'CONNOR, OF FORT WAYNE, MICHIGAN, ASSIGNOR OF ONE-HALF TO GEORGE K. BRADY, OF FORT CRAWFORD, COLORADO.

SOLDIER'S AMMUNITION EQUIPMENT.

SPECIFICATION forming part of Letters Patent No. 373,681, dated November 22, 1887.

Application filed March 23, 1887. Serial No. 232,131. (No model.)

To all whom it may concern:

Be it known that I, STEPHEN O'CONNOR, of Fort Wayne, county of Wayne, State of Michigan, have invented a new and useful Improvement in Soldier's Ammunition Equipment; and I declare the following to be a full, clear, and exact description of the same, such as will enable others skilled in the art to which it pertains to make and use it, reference being had to the accompanying drawings, which form a part of this specification.

My invention consists of the combinations of devices and appliances hereinafter specified, and more particularly pointed out in the claims.

15 In the drawings, Figure 1 is a perspective view of an ammunition equipment and harness embodying my invention and showing by dotted lines at the base the locality of my cartridge-belt. Fig. 2 is a central section from front to rear, showing parts in elevation, of my cartridge-yoke without my cartridge-belt harness. Fig. 3 is a plan view of my cartridge-yoke, showing the cartridges in position, the rows being advanced, with the exception of the portion opposite the neck, so as to carry its line of gravity farther forward. Fig. 4 represents a variation in which the yoke is adapted both as a provision-box and as a cartridge-holder. Fig. 5 is a detached view showing the webbing 30 adapted to receive packages of cartridges instead of separate cartridges for the yoke. Fig. 6 is a view of my improved cartridge equipment, illustrating the belt only as attached to the harness and with the yoke removed. Fig. 7 is a separate view illustrating the flexible rail at the top of the cartridge-belt which engages the traversing rollers. Fig. 8 is a detail view in elevation of the cartridge-belt. Fig. 9 is a detail view in section of the same. Fig. 40 10 illustrates how the webbing on the belt may be made to receive packages of cartridges instead of separate cartridges. Fig. 11 is a cross-section of the piping or cartridge pockets employed on the yoke.

45 It is the object of this invention to produce an ammunition equipment for a soldier which will enable him to carry conveniently a large quantity of ammunition—as, for instance, two hundred and fifty rounds—the same so constructed that a portion may be carried directly upon the shoulders and the remainder in a belt

about the waist—in either case, however, the apparatus being adapted to sustain the weight from the shoulders.

The invention also consists in combining a 55 cartridge-carrier with a ration-box; also, in the peculiar construction of the cartridge-belt and means for rotating the belt about the body; also, in other novel features of construction of the harness and the various parts of the entire 60 apparatus.

In carrying out my invention, A represents a yoke of suitable size for receiving and supporting a quantity of cartridges. I do not limit myself to any particular shape or size of 65 this yoke.

To construct the yoke I take a piece of suitable material, A'. It may be either stiff or flexible, although I prefer to make it flexible throughout, and so prefer to use rubber, leather, 70 or heavy woven fabric. In this an opening, A², is formed to accommodate the neck of the wearer. There is built upon this, by means of similar flexible or other suitable material, a box, A³, in which it is designed to carry unbroken packages of cartridges, and a lid, A⁴, may be hinged thereto at its rear edge in any convenient way, and fastened by straps and buckles *a* or other fastenings at its forward edge when closed. The under portion of this 80 yoke is provided with padding A⁵, so as to distribute the weight upon all parts of the shoulder and across the back and shoulder-blades. Upon the top of the yoke in front at each side of the neck is provided suitable pockets, *a'*, for the reception of the separate cartridges. So, also, there is a similar series of pockets arranged along the whole length of the yoke back of the neck of the wearer. These pockets may be formed in any suitable 85 manner and of any suitable material. I prefer, however, to form them of fabric, with piping projecting from both sides of the same, so as to hold the cartridges one directly over the other, as shown in the sectional view in Fig. 90 11. The webbing is secured at its extremities and also at intermediate points, if found necessary. This cartridge-yoke is designed more especially for use in connection with a harness—such as is shown in Fig. 1—which projects down to the waist, and is there adapted 95 for the reception of a cartridge-belt; but it

may be employed alone without this harness, and in that event might be attached solely by straps A⁶, as shown in Fig. 2, one at each end of the yoke adapted to pass around under each 5 arm.

The harness for supporting the cartridge-belt and for the attachment of the yoke may consist of any suitable arrangement of straps. The following, however, is deemed a good arrangement: Two shoulder-straps, B, extend from the belt over the shoulder and down again to the belt. A brace-strap, B', unites them at the back, and a similar strap, B'', unites them by a buckle in front. A loop, B³, 10 passes under each arm and from that depends a hanger, B⁴. A similar hanger, B⁵, engages the belt-strap behind the back, and farther up is divided off to the two shoulder-straps, as shown. These are all united at the base by 15 rivets or otherwise to a strap, B⁶, which passes around the waist, and its ends are united by a buckle. It is seen that by loosening the buckles at the waist and breast the harness may be readily thrown off. Buckles b are provided 20 on the shoulder-straps to engage straps b' on the yoke, and I prefer to provide two or more such buckles on each shoulder strap, so as to admit of an adjustment of the shoulder-straps toward or from the points of the shoulders to 25 suit the convenience and comfort of the wearer.

My improved cartridge-belt is constructed as follows: There is a foundation or bed piece of rubber, leather, canvas, or other fabric, C. To this is connected suitable pockets, c, for 30 receiving the separate cartridges. If one tier of cartridges is to be carried, there is of course one set of pockets. If two tiers of cartridges are to be carried, there is an upper and a lower series of pockets. These pockets I prefer to 35 make in the usual way of a webbing of fabric with the pockets in the nature of piping, which project from the outer face of the said webbing. So, also, where arranged for two tiers of cartridges, I prefer that the lower webbing 40 shall be of sufficient width to embrace substantially the whole length of the cartridge-shell, so that the cartridge-flange shall rest upon the upper edge of the pocket. The webbing for the upper tier should then be arranged so as 45 to leave a space of an inch (more or less) between the upper and lower piping, so as to facilitate the ready insertion and removal of the cartridges from the latter. The upper tier of pockets should be arranged in quincunx 50 order with respect to the lower tier, so that the balls of the upper cartridges shall rest between the lower cartridges and not upon their primers. This belt is clasped in the usual 55 way about the body by one or more straps and buckles, c'. At intervals along the length of the belt are metallic straps C'. These are secured to the belt by eyelets and lacing, so as to admit of removing them or adjusting them to different points on the belt; or they 60 may be secured by eyelets or rivets, which fasten them securely to the belt. They serve 65 to stiffen the belt from edge to edge. They

also have their upper ends carried over and riveted to a flexible metallic rail, C²—for instance, as shown in detail in Fig. 9. This rail 70 is jointed at intervals, as shown in Fig. 7, so as to flex about vertical pivots, each section being also slightly curved. This rail is provided at its free ends with any suitable means for uniting them, so as to make the rail continuous—as, for instance, by a telescopic joint. Instead of the flexible rail, a suitable band of 75 spring metal might be substituted with a suitable clip for uniting its ends. At the bottom of each depending strap of the harness is an open link, C³, bearing a pulley or roller, c², so that the said metallic rail may be passed into the open link and rest upon the pulleys. The body side of the belt C is preferably of glazed material, so as to readily slide upon the clothes 80 of the wearer. It is thus seen that the belt can be traversed around the body, so as to bring the cartridges to the hand of the wearer, and this is effected by the rail moving upon the rollers c², the open link which retains the 85 roller serving as a guard to prevent accidental disengagement of the rail.

The piping a' upon the yoke A and the piping c upon the belt C may each of them be made of a size sufficient to take a package of 90 cartridges, instead of a single cartridge, as shown in Figs. 5 and 10 at c³; but I would have it understood that this construction is especially adapted for carrying cartridges done 95 up in packages for magazine-guns. The lower 100 tier of pockets (shown in Fig. 10) upon the belt would have to be closed at the bottom to prevent the packages from dropping through; but in the upper tier the lower edges of the packages would rest upon the upper edges of 105 the packages below.

The yoke A may be made in a single piece with a neck-opening large enough to accommodate any wearer, or it may be divided at one or more points, as shown at a² in Fig. 3, 110 in which event suitable lacing should be provided at these points, the object being to lengthen or shorten the yoke to suit the comfort of the wearer. So, also, I would have it understood that, as shown in Fig. 1, the rear 115 tier of cartridges may extend in a line from end to end of the yoke; or, as shown in Fig. 3, that portion immediately back of the neck may be arranged along the rear of the yoke, 120 while the remaining portions may be brought forward upon both sides of the neck, so as to bring the heavier portions or the bullet ends of the cartridges all close to the median line or line of gravity, as shown in Figs. 2 and 3.

I do not of course limit myself to any particular number of cartridges to be carried; but I will now describe the device as adapted for the carrying of two hundred and fifty cartridges.

I would first arrange ninety of them in the 130 two tiers of the belt. I would then locate twenty cartridges upon the forward edge of the yoke on both sides of the neck in two tiers each, and I prefer, as shown in Fig. 3,

that the shells project forward somewhat over the edge of the yoke. I would then open the box A³ and place within it, preferably in packages, sixty cartridges in two tiers. Then having closed the lid I would arrange sixty cartridges upon the lid in two tiers, as shown in Figs. 1 and 2. There is thus provided a supply of two hundred and fifty rounds of cartridges, and all of those upon the belt and 10 those in view upon the yoke in Fig. 1 are readily accessible by the hand of the soldier. To accommodate this one hundred and sixty rounds of cartridges on the yoke would require a structure about eighteen inches in length 15 and five inches in breadth at the base, leaving three inches back and two inches in front of the line which forms the forward edge of the box A³, which line thus becomes substantially the line of gravity. It is thus seen that the 20 load is distributed directly over the shoulders, so as neither to drag backward nor pitch forward.

Care should be taken to so pad the yoke beneath as to relieve from pressure the upper 25 portion of the spine. The padding at the extremities is so disposed as to permit the load to rest easily without cramping the shoulders and so as to permit a free use of the arms in aiming and loading the piece.

30 The straps beneath the arms are relieved from strain, so as not to injuriously effect the axillary nerves. The shoulder-straps are carried well toward the shoulders to avoid compression of the lungs and heart, and the breast- 35 strap should for the same reason be arranged well up toward the neck. The belt by this construction is suspended wholly from the shoulders, as it should be, and so the kidneys, the liver, and stomach are relieved from injurious pressure.

In Fig. 4 is shown a variation, in which the yoke is adapted for carrying provisions, and may also carry, as before explained, one hundred rounds of cartridges upon its top. It is 40 of course apparent that the box here exhibited might be filled with packages of cartridges as well as with provisions. I would have it understood that this harness and belt may be employed without the yoke; also, that the 45 yoke may be employed alone, either with or without the harness; also, that if the yoke and harness are employed together it may be either with or without the cartridge-belt. So, also, I would have it understood that while this has 50 been described and illustrated as a cartridge equipment, the same is equally adapted for the use of sportsmen who find it necessary to carry a considerable quantity of ammunition. So, also, the straps represented in the drawings may be of leather, or they may be of water-proof or other fabric—such as webbing or 55 canvas.

As the cartridges are represented in Fig. 1, the yoke with its charge would be about one 60 inch and a quarter in vertical thickness at its forward edge, and about two and a half inches in thickness along its rear or higher portion.

It is thus apparent that it will not interfere with the convenient carrying of a gun upon the right or left shoulder, and in order to preserve the stock of the gun from injury by rubbing against the cartridge-shells, I propose to provide suitable cushions, A⁷, which shall project forward over the edges of the cartridges. These cushions may be suitably attached to 75 the piping a', and be flexible, so as to admit of ready access to the cartridges beneath. I purpose, also, to provide the shoulder-straps of the harness with rests of metal or other suitable material, the same to be located so as to 80 support the lower rear edge of the yoke. Such rests are indicated at b² in Fig. 1.

When the yoke is used without the cartridge-belt and harness, it would be desirable to employ a tight belt about the waist and 85 connected with the yoke by suitable straps. The strap B⁶ may be made of sufficient width to answer the purposes of such a tight belt, the same being properly strapped to the yoke.

In a device of the above description a soldier 90 in expending ammunition has full power to regulate and maintain the proper distribution of weight by first using the cartridges on the yoke, and then the top row of the belt, before those in the lower row of the belt are touched. 95

Having thus described my invention, what I claim is—

1. An ammunition equipment consisting of a yoke having in combination therewith means for securing it to the shoulders of the wearer, 100 said yoke provided with a series of cartridge-pockets, substantially as described.

2. An ammunition equipment consisting of a yoke having in combination therewith means for securing it upon the shoulders of the wearer, 105 said yoke provided with one or more boxes and with a series of cartridge-pockets, substantially as described.

3. An ammunition equipment consisting of a yoke having in combination therewith a suitable harness provided with an ammunition-belt at its base, said belt and yoke provided with cartridge-pockets, substantially as described.

4. An ammunition equipment consisting of 115 a yoke having in combination therewith a suitable harness provided with a revolving ammunition-belt at its base, said belt and yoke provided with a series of cartridge-pockets, substantially as described.

5. An ammunition equipment consisting of a yoke provided with means for engaging the same upon the shoulders of the wearer, said yoke provided with one or more boxes and a series of cartridge-pockets, and suitable padding engaged with the under side of said yoke, 125 substantially as and for the purpose described.

6. An ammunition equipment consisting of a yoke provided with means for engaging the same upon the shoulders of the wearer, said 130 yoke constructed to receive individual cartridges or packages of cartridges, substantially as described.

7. The harness consisting of shoulder-straps,

breast and back straps, and suspending-straps, a belt uniting the lower extremities of said suspending - straps, having in combination therewith a cartridge - belt supported about 5 the waist upon said harness, the construction being such that said cartridge-belt will be supported upon the shoulders of the wearer, substantially as described.

8. A cartridge-yoke adapted to rest upon 10 and with means for securing it to the shoulders of the wearer, the same provided with pockets formed of webbing or fabric, with piping projecting therefrom and adapted for receiving and retaining the individual cartridges, substantially as and for the purposes 15 described.

9. A cartridge-yoke adapted to rest upon and means for securing it to the shoulders of the wearer, said yoke adapted to receive and 20 retain a quantity of cartridges upon both sides of the neck of the wearer, and another quantity extending from shoulder to shoulder back of the neck of the wearer, substantially as described.

25 10. A cartridge-yoke, A, adapted to be supported upon the shoulders of the wearer, the same divided at one or more points and provided at these points with adjustable fastenings, whereby the yoke may be lengthened or 30 shortened to accommodate the wearer, substantially as described.

11. The combination, with a cartridge-belt, of a flexible rail adapted to engage and traverse upon rollers connected with the harness, 35 substantially as and for the purpose described.

12. The combination, with a harness, of rollers or pulleys located at intervals about its circumference, and in combination therewith a cartridge-belt provided with a flexible rail at its upper edge, adapted to engage and traverse upon the said rollers, substantially as and for the purpose described. 40

13. The combination, with a cartridge belt, harness straps C', and links C², of a flexible rail made up of curved sections united by vertical pivots at their extremities, said rail being movably supported in said links, substantially as and for the purposes described. 45

14. The harness consisting of shoulder-straps, breast and back straps, and suspending-straps, provided with a belt uniting the lower extremities of their depending ends, the same adapted to sustain the cartridge-belt and to support the yoke upon the shoulders, substantially as and for the purpose described. 50

15. The combination, with a cartridge-belt, of a lower tier of piping adapted to receive cartridges projecting therein to their flanges, and an upper tier of piping an inch (more or less) above the former and adapted to receive 60 cartridges in quineunx order with respect to the lower tier, substantially as described.

In testimony whereof I sign this specification in the presence of two witnesses.

STEPHEN O'CONNOR.
